UNITED STATES PATENT OFFICE.

JOSEPH H. ADDLER, OF BROOKLYN, NEW YORK, ASSIGNOR TO FULLCLEAN MANUFACTURING CORPORATION, OF BRIDGEPORT, CONNECTICUT, A CORPORATION OF DELAWARE.

TOWEL CABINET.

Application filed May 28, 1927. Serial No. 195,048.

This invention relates to towel cabinets of the type comprising a plurality of rollers within the cabinet, one carrying a roll of clean towelling adapted to be drawn outwardly from the cabinet in suitable lengths for drying purposes, others being operative to take up the soiled towelling in substantially the same ratio as it is drawn out, and another being operatively connected with the take-up rollers to actuate the same; this last mentioned roller being operated by the frictional engagement of the towel therewith in being drawn from the cabinet.

In cabinets of this type as usually constructed, it has been necessary to employ a braking means in connection with the towel carrying roller for preventing overthrow of the latter when rotated under the pulling action of the towel; this overthrow being objectionable in that it tends to loosen the wraps of the supported towelling, in which event the outward feeding or withdrawal of the towelling from the cabinet in an even and smooth condition is prevented.

The braking means for these carrying rollers as heretofore employed have not been found to be effective however, and it has therefore been an object of the present invention to provide an improved means for preventing overthrow of such rollers which will be effective. This object is attained by means of the novel construction and arrangement of parts as hereinafter described and claimed and as illustrated in the accompanying drawing, in which—

Fig. 1 is a front view of a towel cabinet equipped with my invention, and

Fig. 2 is a vertical section through the same on line 2—2, looking in the direction indicated by the arrows.

The cabinet, which may be of any desired construction or design, is here shown as comprising a body portion 1 having a door 2 at the front side thereof, said door being hinged at one end to the body, as at 3, and at its opposite end being secured in closed position by suitable fastening means, such as the lock 4. These parts may be formed of any suitable material, but preferably are formed of metal.

Located within the casing 1 adjacent opposite ends thereof are a pair of frame or bracket plates 5, 5 which are secured in position by suitable fastening means, such as the bolts 6. These bracket plates provide end bearings for a plurality of towel supporting

and operating rollers to be presently described, and as the plates are substantial duplicates, only one of them has been here shown.

Suitably journaled in these bracket plates adjacent the top part of the cabinet is a roller 7 upon which the roll of clean towelling, indicated at 8, is adapted to be mounted. When so mounted, the leading end of the towel is led from the front side of the roll downwardly beneath a stationary guide rod 60 and from thence forwardly through an opening 9 in the front wall of the cabinet to and over a guide roller 10, which latter is journaled in extensions of the bracket plates which project through the opening 9 in the cabinet to support the roller 10 at the front side thereof. From this guide roller 10, the towel depends in loop form, as at 7, in convenient position for use, the towel at the rear side of the loop passing backwardly through the opening 9 and down to a take-up or re-winding device comprising a pair of rollers 11 and 12 between which the towel is passed, one of these rollers being operated by means to be presently described to pull the engaged towel into the cabinet and re-wind it upon the other, as shown in Fig. 2.

As the towel is drawn outwardly from the clean roll, the soiled part thereof is adapted to be drawn back into the cabinet and re-wound upon the roller 12 in substantially the same length of loop at all times at the front side of the cabinet. This is accomplished in the following manner: A roller 8 is journaled at its opposite ends in the bracket plates 5, 5, in position to have the roll of towelling on the roller 7 bear directly thereagainst, whereby, as said roll is rotated by the pulling of the towel from the cabinet, it will act through its frictional engagement with the roller 8 to rotate the latter, and such actuation of this roller is utilized to operate the re-winding roller 11 through suitable driving connections. These connections, which are duplicated at the opposite ends of the rollers, comprise a sprocket wheel 14 attached to one end of the roller 8 and operatively connected through a sprocket chain 15 with a second sprocket wheel 16 attached to one end of the re-winding roller 11, which latter cooperates with the roller 12 to effect a re-winding of the towel.

This driven roller 11 is journaled in the lower ends of a pair of swinging arms, 110

such as 18, pivotally mounted on hub extensions of the roller 8, whereby it may move bodily with respect to the roller 12 to accommodate itself to the increasing diameter of 5 the roll of soiled towelling being wound thereon, and it is yieldingly held in cooperative relation to the roller 12 to effect winding of the towel thereon by means of springs 19 connecting with upper extensions 20 of the 10 arms 18, as shown in Fig. 2. As a further means of guiding the roller 11 in its movements radially of the roller 12, the bracket plates 5 are provided with arcuate slots 21 through which the end journals of the roller 15 11 extend.

In accordance with my present invention, the actuating roller 8 is mounted in a position below and in advance of the towel carrying roller 7 whereby it will engage the roll of 20 towelling on said roller at a point forward of the vertical plane of its axis and below the horizontal plane thereof, as shown in Fig. 2; it having been found in practice that the engagement of the roll of towelling at or about 25 such point by the roller 8 acts to retard or brake the forward rotation of the roller under the pulling action thereon in withdrawing the towel from the cabinet more effectually than the braking means applied directly to the 30 towel carrying roller as heretofore employed; and such braking action is made more effective by means acting to hold the roll of towelling in close contact with the roller 8 during 35 unwinding of the same and preventing raising or "jumping" of the same with respect to the roller 8 such as might occur as the result of a quick outward pull or jerk of the towel by a user. This holding means as here shown comprises guide-ways on the inner or op-

posing faces of the bracket plates 5, such as 40 25, for receiving the end bearing journals 26 of the roller 7, these guide-ways being inclined and extending from a point back of and above the roller 8 to a point adjacent the latter whereby the roller 7 with the supported towelling will normally gravitate 45 towards the roller 8 as the diameter of the roll of towelling decreases during use of the same and thus act to maintain proper contact 50 of the roll of towelling with the roller 8. Furthermore, these guide-ways, by reason of their inclination, act in the nature of wedges 55 to hold the roll of towelling against the roller 8 when being rotated by the outward feeding or withdrawal of the towelling.

As a means to facilitate the positioning of the roller 7 within the guide-ways and its removal therefrom, grooves 30 are provided in the bracket plates which lead upwardly 60 from the guide-ways in a direction towards the front of the cabinet and in position convenient for access at such point.

What I claim is:

A towel cabinet comprising a roller for carrying a roll of towelling for unwinding in a clockwise direction from the top of the roll, a second roller mounted in front of the cabinet below said first mentioned roller for engagement with the towelling thereon, and guide-ways in which the towel carrying roller 65 70 is slidably mounted, said guide-ways being inclined toward said second roller, whereby said second roller will grip the roll of towelling and prevent unwinding of the same upon any sudden pull on the external portion 75 of said towelling.

In testimony whereof I affix my signature.

JOSEPH H. ADDLER.
